Edith Jean Blanc Miller, Chicago, Ill., assignor
to Associated Products, Inc., Chicago, Ill., a corporation of Illinois

Application January 19, 1946, Serial No. 125,726

Term of patent 3½ years

(Cl. D58—26)

To all whom it may concern:

Be it known that I, Edith Jean Blanc Miller, a citizen of the United States, residing at Chicago, in the county of Cook and State of Illinois, have invented a new, original, and ornamental Design for a Bottle Cap, of which the following is a specification, reference being had to the accompanying drawing, forming part thereof.

Fig. 1 is a side elevation of a bottle cap, showing my new design.

Fig. 2 is a front elevational view thereof.

Fig. 3 is a plan view thereof.

Fig. 4 is a rear elevational view thereof.

I claim:

The ornamental design for a bottle cap, substantially as shown.

EDITH JEAN BLANC MILLER.
